UNITED STATES PATENT OFFICE.

ANDRE JANER, OF FLUSHING, NEW YORK.

CIRCUIT CLOSER.

Original application filed May 23, 1925, Serial No. 32,303. Divided and this application filed January 12, 1926. Serial No. 80,702.

This invention relates to circuit closer and is a division of my application, Serial No. 32,303, filed May 23, 1925, relating to signal system.

5 One of the more important objects of my invention is to provide an alarm initiating device which is cheap to manufacture, can be reset after actuation, as by fire, with a minimum possibility of maladjustment, and 10 one which is positive and reliable in operation.

Further objects, advantages and features of my invention will more fully appear from the detail description below taken in connection with the accompanying drawings, in which:

Fig. 1 shows in plan view the preferred form of my improved alarm initiating device with the cover therefor removed.

20 Fig. 2 shows a plan view of the alarm initiating device with the cover in place, and

Fig. 3 shows in elevation a cross section through the alarm initiating device along the line 3—3 (see Fig. 2).

25 Referring to the drawings in detail, the reference numeral 1 designates a base of suitable electrical insulating material provided with a supporting post 2. Mounted on and secured to the base 1 are two switch contact members 3 and 4 provided respectively with contact faces 5 and 6. Mounted on and secured to base 1 is also an electrical conducting member 7 which supports and is electrically connected to a resilient arm member 8 of electrical conducting material. The member 8 terminates in a switch member 9 which, by means presently to be described, is normally held out of electrical contact with the faces 5 and 6 of contact members

40 3 and 4. The supporting post 2 terminates at its upper end in shouldered boss 10 which is polygonal or irregular shaped in cross section. A disc 11 of readily combustible material such as celluloid, is provided with

45 a central hole shaped to snugly fit the boss 10 to prevent relative rotation of the disc 11 with respect to said boss 10. A downwardly depending projection 12 is formed as a part of the fusible disc 11. This may readily be 50 done by cutting two slits from the edge towards the center of disc 11, at the proper positions, and bending that part of the disc between the two slits at right angles to the

plane of the disc as shown. When the combustible disc is normally in place on the boss 55 10 of the supporting post 2 the depending projection 12 of said disc serves to hold the switch 9 of the spring contact arm 8 from engagement with contact faces 5 and 6 of members 3 and 4. This projection 12 will 60 hold these electrical contacts out of engagement until the combustible disc is removed or destroyed, as by fire.

A closure member 13 is provided with a series of holes 13^a around its periphery to 65 expose the combustible disc 11 to the surrounding atmosphere. This closure member is preferably held in place by a central screw 14 which fits into a threaded hole in the post 2. This screw 14 also serves to hold 70 the combustible disc in position on the shouldered boss 10. It will be noted that the removal of the screw 14 permits easy access to all parts of the alarm initiating device. The wires which serve to connect 75 parts 3, 4 and 7 to the various circuits of the alarm system are adapted to enter through suitable perforations provided in the base 1, and are suitably connected to these several parts as by one of the screws which secures 80 these parts to the base. It will also be noted that contact is made between members 3, 4 and 9, when the device is actuated, in such a manner that a scraping or wiping action takes place between the member 9 on 85 the one hand and the members 3 and 4 on the other. This insures that any dirt or accumulation on these members is disturbed or removed thus assuring a proper contact between said members.

90 From the foregoing it will be seen that I have devised a new form of circuit closer. It is to be expressly understood however, that the device herein illustrated, described and claimed is merely the preferred embodiment of my invention. Accordingly I do not limit myself to the exact construction illustrated and described as many changes may be made in point of detail and other embodiments resorted to without deviating 95 from the true spirit and scope of my invention.

What I claim is:

1. In an alarm initiating device, a supporting base, a plurality of electrical contact 105 members mounted on said base, a contacting

arm fastened to one of the said contact members and adapted to come into sliding frictional contact with one or more of the other contact members, and a readily combustible link adapted to hold the said contacting arm out of engagement with the last mentioned contact members, and a perforated cover for said combustible link and said contacts, and means comprising a single screw for holding 10 said cover and said fusible link in position.

2. A renewable link for fire alarm circuit closers comprising a mounting post and a pair of contacts biased together, said link comprising a disc of combustible material 15 having an opening for mounting on said post, and carrying thereon an arm for maintaining said contacts spaced apart.

3. A renewable link for fire alarm circuit closers comprising a mounting post of non- 20 circular cross-section, and a pair of spring contacts biased together, said link comprising a disc of combustible material having an opening therein corresponding to the cross-section of said mounting post, and carrying 25 thereon a depending arm for maintaining said contacts spaced apart.

4. An alarm initiating device comprising a circular supporting base of insulating material, a plurality of contact members of 30 conducting material mounted on said base, a contacting arm fastened to one of said members and adapted to come into sliding frictional contact with one or more of the other contact members, a central supporting 35 post projecting upwardly from said base, a flat circular celluloid element mounted upon said post and adapted to hold said contacting arm out of engagement with the last mentioned contact members, and a perforated cover for said device supported by 40 said central post.

5. An alarm initiating device, comprising a make and break device, and a disc of celluloid material having a portion within its 45 periphery extending at an angle therefrom which portion normally serves to maintain the make and break device in open position.

6. An alarm initiating device comprising a circular supporting base of insulating material, a plurality of contact members of 50 conducting material mounted on said base, a contacting arm fastened to one of said members and adapted to come into sliding frictional contact with one or more of the other contact members, a central supporting 55 post projecting upwardly from said base, a flat circular celluloid element mounted upon said post in parallel relation to said base and having a portion within its periphery extending downwardly therefrom to hold said contacting arm out of engagement with the last mentioned contact members, and a perforated cover for 60 said device supported by said central post and adapted to hold said element in position on said central post.

7. An alarm initiating device comprising a circular supporting base of insulating material provided with a central post projecting upwardly therefrom, a plurality of contact members of conducting material 70 mounted on said base, a flat circular celluloid element mounted upon said post in parallel relation to said base and having a portion within its periphery extending downwardly therefrom, a contacting arm located 75 between said base and element which is fastened to one of said members and adapted to come into sliding frictional contact with one or more of the other contact members, the downwardly projecting portion of said 80 flat circular celluloid element being adapted to hold said contacting arm out of engagement with the last mentioned contact members, and a perforated cover for said device supported by said central post and adapted 85 to hold said element in position on said central post.

8. A circuit closer for fire alarm systems comprising a pair of contacts biased to make contact with a scraping action so as to effect 90 metallic contact through surface layers of accidental insulation and a thermal release comprising a combustible disc having an arm attached thereto for holding said contacts apart.

9. A circuit closer for fire alarm systems comprising a pair of contacts biased to make contact with a scraping action so as to effect 100 metallic contact through surface layers of accidental insulation, and a thermal release comprising a combustible disc carrying a projecting arm for holding said contacts apart.

10. An alarm initiating device comprising a supporting base, a plurality of contact members mounted on the base, a contacting arm fastened to one of the members and adapted to come into sliding frictional contact with one or more of the other contact members, a supporting post projecting upwardly from 110 the base, an element mounted on the post, and a combustible stop carried with the element and adapted to hold the contacting arm out of engagement with the last mentioned contact members.

11. An alarm initiating device comprising a supporting base, a plurality of contact members mounted on the base, a contacting arm fastened to one of the members and adapted to come into sliding frictional contact with one or more of the other contact members, a supporting post projecting upwardly from the base, an element mounted on the post, a combustible stop carried with the element and adapted to hold the contacting arm out of engagement with the last mentioned contact members, and a cover for 125 the device supported by the post.

12. An alarm initiating device comprising a supporting base, a plurality of contact 130

members mounted on the base, a contacting arm secured to one of the members and adapted to come into contact with one or more of the other contact members.

5 supporting post projected upwardly from the base, an element mounted on the post and a celluloid stop carried on the element and

adapted to hold the contacting arm out of engagement with the last mentioned contact members.

In testimony whereof, I have hereunto set my hand this 5th day of January, 1926.

10

ANDRE JANER.
